UNITED STATES PATENT OFFICE.

WILBUR C. POTTER AND EDWARD H. STINES, OF NEW BRUNSWICK, NEW JERSEY.

ATTACHMENT FOR KNITTING-MACHINES.

1,398,570.

Specification of Letters Patent. Patented Nov. 29, 1921.

Application filed June 29, 1918. Serial No. 242,528.

To all whom it may concern:

Be it known that we, WILBUR C. POTTER and EDWARD H. STINES, citizens of the United States, residing in New Brunswick, in the 5 county of Middlesex and State of New Jersey, have invented certain new and useful Improvements in Attachments for Knitting-Machines, of which the following is a specification.

10 Our invention relates to an improved attachment for knitting machines; particularly an attachment which is designed to stop the knitting machine when, for any reason, the knitting operation should be 15 temporarily discontinued.

The primary object of our invention is to provide an attachment that can be applied to a knitting machine and that will be constituted of relatively few parts, capable of 20 being easily and cheaply manufactured and quickly assembled and adjusted; and adapted to be readily repaired in case of damage to any of the parts which the attachment comprises.

25 Other objects and advantages of our invention will more fully appear from the following specification which sets forth one or more forms of an attachment made according to our invention. This disclosure 30 however, is illustrative only, as we may change the structure of what is actually shown herein, without departing from the scope and spirit of our invention, to the full extent indicated by the general meanings of 35 the terms in which the appended claims are expressed.

On the drawings, which are part of this specification,

Figure 1 is a side elevation, partly in 40 section, of an attachment for a knitting machine made according to our invention.

Fig. 2 is a top plan of the attachment shown in Fig. 1, with the cover removed.

Fig. 3 is a section on the line 3-3 of 45 Fig. 2.

Fig. 4 shows a modified form of arm or bracket which is an important part of our invention.

Fig. 5 is a top plan of said arm,

50 Fig. 6 is an end view of said arm showing also certain elements which it supports.

Fig. 7 is a top plan of the lower part of 55 an attachment made according to our invention illustrating certain parts which control trip mechanism by which the stopping of the knitting machine is brought about;

Fig. 8 is a view of a detail in connection with Fig. 7;

Fig. 9 is a view of a detail in connection with Fig. 1;

Fig. 10 is a front view, and

Fig. 11 a side view of an especial kind of thread-engaging element and guide to be mounted on our improved attachment.

On the drawings, the same numerals of 65 reference identify the same parts throughout.

Our attachment for a knitting machine, as shown particularly in Fig. 1, includes a head which is made up of a lower casing 70 1 and an upper casing 2. The upper casing 2 is superposed on the lower casing 1 and closes the top of same; the two casings being secured together, when the attachment is finished, in any suitable manner. We provide a cover 3 which closes the top of the upper casing 2 and from the bottom of the lower casing 1 projects a central boss 4 which is hollow to receive the upper end of the stem or shaft of the knitting machine 80 to which the attachment is to be applied. Thus the attachment can be mounted on the knitting machine in operative position. The lower casing 1 bears certain mechanism, including a trip; which, when actuated, allows 85 certain parts of the knitting machine, not shown, to come into play and cause the knitting machine to cease operating; the mechanism in question being controlled by the thread 5. We also affix to the upper casing 2 a number of arms 6, which extend radially outward from the attachment, and have associated therewith certain elements which are engaged by the thread 5; and, 90 which under certain conditions, are disengaged from this thread to allow the trip mechanism to act. Inside the casing 2 we dispose suitable tension devices which act upon the elements associated with arms 6 and engaging the thread 5 and serve to 95 enable the operator to effect an adjustment of the tension to which the thread 5 may be subjected before it becomes disengaged from the aforesaid elements associated with the arm 6.

The arms 6 may be present in any number according to the design of the particular attachment, eight of these arms being indicated for example, in Fig. 2. Each arm is detachably mounted; and for this purpose 110 the upper casing 2 is provided with an encircling flange 7 at its rim which fits into a

recess in the end of each arm and thus permits the arm to be secured in place. The recess in question forms two lugs or jaws in the end of each arm 6, one of these lugs 5 abutting against the cover 3, and the other abutting against the side of the casing 2 below the flange 7; and the arm may be secured by a screw or any suitable fastening device engaging the two lugs and the flange 10 7. The arms 6 are all identical, both as to structure and the parts or elements supported by them; hence we need refer hereinafter to but one of these arms 6.

On the outer edge of each arm is an enlargement 8, to which is affixed a combined guard and guide 9 for the thread 5. This guard and guide is disclosed in the patent of W. C. Potter, No. 1,326,371, December 30, 1919, and no claim to the structure of this 15 20 guard is made herein. It comprises a pair of arms 10 secured to the top and bottom of the enlargement 8; and terminates at its opposite end beyond the junction of the arms 10 in a tail 11. It is concave on the side 25 facing the casing 2 and convex on its opposite face; and it coöperates with a bell-crank lever 12 which has a bearing 13 to enable it to be mounted on a pivot pin extending downward at an incline from the 30 under side of the arm 6. At its forward end the longer arm of the bell-crank 12 terminates in a fork, having one prong extending beyond the guard 9; and the adjacent or upper edge of this guard, indicated by 35 numeral 14, is curved downward; the shape of the guard being such that this edge not only extends downward from the top of the enlargement 8, but also toward the casing 2. Hence, to get the thread in the fork of the 40 lever 12, one has only to put the thread on the edge 14 of the guard 9 and let it slip down until it engages the extending prong above mentioned. It then passes behind the tail 11 and remains in the fork under normal 45 conditions. As shown in Figs. 1 and 2, the plane of the prongs of the fork are approximately parallel to the adjacent portions of the guard 9 and the guard at no time obstructs the entrance to the space between the prongs. Adjacent the bearings 13, the bell-crank 12 has a shorter arm which is 50 engaged by an arm 15 of a rock-shaft 16; which is located beneath the arm 6 and extends along the under side of same to the 55 inside of the casing 2. Near the casing 2 and on the outside of the latter, this arm carries a fixed hook 17; and the thread 5, after leaving the lever 12, passes over and engages this hook on its way to the knitting 60 needles. The hook 17 may be made out of a single stamping, and may have an overturned lip 18 to afford a smooth rounded surface over which the thread may run, and be provided with a bearing remote from the 65 lip to enable the hook to be mounted on the

rock-shaft 16, as shown in Figs. 1 and 4. The bearing for the inner extremity of the shaft 16 consists of a hole or opening in the casing 2 through which the shaft 16 passes to the inside thereof; and the bearing for 70 the end of the shaft carrying the arm 15 may be in the form of a perforated lug 19 having a bent over end with a hole therethrough to enable it to be secured by a screw to the bottom of the arm 6. 75

Normally the shaft 16 will act through the arm 15 to hold the lever 12 so that the fork will retain the position shown in Figs. 1 and 2, the lever 12 then having its longer arm with the prongs thereon then making 80 contact with a projection shown in Fig. 1 on the lower end of the enlargement 8, this projection serving as a stop for the lever 12; the hook 17 likewise maintaining operative position to be engaged by the thread 5. 85 The shaft 16 is connected for this purpose to certain tension devices in the casing 2, comprising springs for acting upon the shafts 16 and means for adjusting the tension of these springs. These devices are 90 mounted in the casing 2 by a central post or stud 20, fixed to the bottom of the casing 2 and surrounded by a central boss as shown in Figs. 1 and 3. On this post is disposed a disk 21, which can turn to a certain extent 95 around the post 20, and rests upon the boss at the bottom of the casing 2, so that it is supported thereby. This disk has a central hub or bearing 22 by which the post 20 is directly engaged. Above the disk 21 is a 100 second disk, having a similar hub or bearing which extends downward and engages or abuts the hub or bearing of the first disk, resting thereon and keeping the two disks spaced apart, one above the other. On the 105 upper end of the journal or post 20 is a head, and at its lower end, this journal is flattened against the outside of the bottom of the casing; so that the two disks, while free to turn on the post, are held against 110 displacement therefrom.

Each of the disks 21 mounts a plurality of arms 23, which may be in the form of short wires or rods bent to provide eyelets on their outer ends and having their inner ends driven into or otherwise engaging holes in the rims of these disks. Each arm is connected by a spring 24 to an arm carried by the inner end of one of the rock-shafts 16, the arms in question being indicated by the 115 number 25 and being in the form of wire suitably bent to engage the inner ends of the shafts 16, and having eyelets to enable the spring 24 to be secured thereto. To the lower face of the lower disk 21 we attach 120 a pin or plug 26; pivotally mounting the same in this disk so that it can turn with respect thereto; and having below the disk in one side a threaded opening to engage a 125 screw or bolt 27. This bolt passes through 130

the side of the casing 1 and terminates outside the casing in a head 27^a which may be provided with a kerf 27^b. Hence, by means of a screw driver or other tool, the bolt 27 can be turned and the lower disk 21 may thus be rotatably adjusted on the post 20. To the upper disk 21 is pivotally secured a similar pin or plug which extends downward through a slot 28 in the lower disk and 10 has a threaded opening in its lower end to receive the threaded end of another bolt 27 which can be turned from the outside of the casing in the same way for the purpose of adjusting the upper disk; the two bolts 15 being arranged side by side, as indicated in Fig. 2. As shown in Figs. 1 and 2, the arms of the upper disk are secured to alternate shafts 16 and the arms of the lower disk are secured to the remaining shafts 16, and the 20 arms 25 connected to the upper disk extend upward, while the arms of the remaining shafts 16 connected to the lower disk extend downward. The springs 24, therefore are divided into two sets, one set being connected 25 to the arms 25 extending in one direction around the casing, and the other set for the arms 25 extending in the opposite direction. By manipulating the screws 27, the disks 21 can be turned upon the journal 20 to 30 vary the tension of the springs and thus adjust the degree of pressure which the arms 15 exert upon the bell-crank levers 12.

We may make the disks 21 by casting or in any other suitable manner; and the arms 35 23 can be quickly attached to same. Likewise the disks can be easily assembled in the casing 2, and the arms 23 thereon can be readily connected by springs 24 to the arms 25 on the shafts 16; and the make up of 40 these disks and arms does not entail very great expense. Further the particular structure of the arm 6 not only enables it to be readily mounted on the casing 2, but also in case of accident or damage to one of these 45 arms, it can be taken off and replaced with a new arm without having to dismount the head from the knitting machine. Hence, any damage to the attachment does not require the removal of the attachment from 50 the machine and return of the attachment to the factory for repairs. In fact, in case of breakage or derangement of any of the parts above mentioned, the attachment can be repaired at once and the machine need not 55 be out of operation for any extended period.

The trip mechanism, as stated above, is located in the lower casing 1; which has a central portion of its bottom depressed as shown at 29 in Fig. 1 to accommodate this 60 mechanism. Inside this casing is a flange or rim 30 extending upward from the bottom around the depressed portion 29 and located some distance from the inside wall of the casing; forming with the depressed 65 portion 29 of the bottom, a chamber in which

the trip mechanism can be advantageously disposed. The mechanism in question comprises a slidable member 31 in the depressed portion of the bottom of the casing 1 and having its end projecting through the casing 70 to the outside of the same just below the flange 30. Normally this member 31 will be in the position shown in Fig. 7. At its outer end it will be connected to mechanism 75 adapted to stop the knitting machine by shifting the belt off from the main driving pulley, and to do this the member 31 is operated by a spring 32 in the casing 1. The slidable member 31 is held in the position it occupies in Fig. 7 by parts such as are 80 shown in the patent to Crawford, No. 510,839, granted December 12, 1893, including a trip or trigger which prevents the spring 32, though under tension, from withdrawing the member 31. We also put in the casing 1 a 85 rotatable disk 33 which will be above the member 31 and surrounded by the flange 30. This member will be mounted on a pivot pin 34, engaging a bearing in the bottom of the casing 1; and it will also have a pin or projection 35 which extends downward adjacent the trip or trigger above mentioned. When the disk 33 is turned clockwise with reference to Fig. 7, the pin 35 will strike the trip or trigger and cause the member 31 to be 90 released. Then the member 31 will be pulled to the left by the spring 32, to cause the shifting of the belt from the driving pulley and the stopping of the knitting machine.

In order to rotate the disk 33, we provide a number of recesses in its edge, each recess terminating in an abrupt radial shoulder 36. These shoulders are each engaged by an arm 37 on a spindle 38; there being as many of these spindles as there are arms 100 6 and each of them being mounted in holes or bearings in the flange 30 and the wall of the casing 1; and extending through to the outside of this casing 1. Preferably we may make these spindles out of metallic 105 rods and provide the arms 37 by bending over the inner ends thereof. To the end of each of these spindles 38, which are located in each instance directly below the arms 6, we affix a finger 39 which may be 110 a bent wire and have a pair of latterly extending projections 40. These fingers 39 extend upward toward the arms 6 and normally occupy a slightly inclined position, that is to say, they will lean so that the 115 projections 40 thereon will be a little closer to the observer viewing Fig. 1 than the shaft 38 on which the finger may be mounted. See Fig. 9. These fingers each co-operate with a frame 41 secured to the under side of the adjacent arm 6, the lower part of this frame having parallel transverse slots 42 through which the projections 40 may pass. The frames 41 may be made by stamping the same out of sheets or pieces 120 125 130

of metal and be secured to the arm 6 by bending over their upper edges and passing screws through same to engage the arm. See, for example, Fig. 4. Each frame will 5 be in front of the shaft 16 carried by the arm which supports it and will further be provided with an opening 43 into which the hook 17 can project.

The relation of the arms 37 to the shoulders 36 of the disk 33 is best illustrated in Fig. 8; and the manner in which the threads 5 engage the levers 12 and the hooks 17 operate with respect to the fingers 39 is best illustrated in Figs. 1 and 9. After 15 leaving the hook 17 the thread 5 will pass down behind the frame 41, with reference to Fig. 1, but in front of the projections 40 projecting through the slots 42; that is it will pass between the frame and the projections 40 and hold the projections of the finger 39 so that the arm 37 at the inner end of spindle 38 will not act upon the adjacent shoulder 36 of the disk 33 with sufficient force to move this disk and release 25 the member 31. The position of each finger 39 will be slightly inclined at this time, with the action of gravity, tending to cause this finger to fall over to the right as indicated in Fig. 9, counterbalanced by the 30 thread engaging the projections 40. If the thread 5 should break, the finger 39 can fall to the right and move the disk 33 to actuate the trip and enable the member 31 to be withdrawn and stop the knitting machine 35 at once. The same result will follow if the thread should get tangled and catch anywhere, so that the tension of the thread as it is drawn to the knitting needles will pull the fork of the lever 12 away from the guard 40. In such a case the fork will act upon the arm 15 to rotate the shaft 16, swinging the hook 17 at the same time so that the thread drops off this hook. Hence, the 45 finger 39 will be released as before to actuate the disk 33 and stop the machine. Therefore, in case any one of the threads 5 going to the knitting machine by way of one of the arms 6 of our attachment should become broken or tangled or knotted, the machine will automatically stop until the 50 defect in the thread can be attended to.

In Figs. 4, 5 and 6 we show a modified form of arm indicated by the numeral 44. This arm is made by pressing or stamping, 55 whereas the arm 6 must be made by casting. The arm 44 has its inner end shaped to fit against the casing 2, just below the flange 7; being both rounded to correspond with fillet between the lower face of this 60 flange and the side of the casing; and made concave to fit the outside curvature of this casing. It is provided with a pair of projections 45 struck up to abut against the rim of the flange 7 and between these projections and the adjacent end of the arm is

a hole which is intended to register with a similar threaded hole in the flange 7 to receive the fastening screw which secures it to the casing. Adjacent the projections 45, and near one edge of the arm 44 the arm 70 44 may be provided with a couple of flats indicated in Fig. 5, to enable the upper bent over end of the frame 41 to be applied and fastened to the same; and adjacent the outer end of this arm we may 75 provide a couple of down-turned projections 46 and 47 in longitudinal alinement with each other and struck out like the projections 45. The projection 46 will have a hole therein and serve as a bearing for the 80 shaft 16 and the other projection 47 will have a hole to receive the pivot pin of the bell-crank lever 12. At its outer end, the arm 44 will be bent laterally in both directions, that is downward and outward and then 85 upward and inward, as shown in Fig. 4; thereby providing a couple of portions 48 which may have threaded holes to secure to these portions 48 the ends of the arms 10 of the guard 9. Adjacent the projection 90 47 there may be a projection 49 to act as a stop for the lever 12 when it is actuated by the arm 15 toward the guard 9.

While we prefer the frame 41, we may also drill a couple of holes 50 in the arm 6 95 and in the arm 44 near the end which is fastened to the flange 7 to enable us to attach to the arm a frame made up of wire instead of a frame made out of a metal stamping, as above described. Such a frame will be affixed merely by forcing the ends in the holes 50 from below and when in position it would coöperate with the fingers 39 in the same way as the frame 41.

As shown in Figs. 7 and 8 the disk 33 is 105 made out of sheet metal and the shoulders 36 are in-cut edges presented to the arms 37 on spindles 38.

In Figs. 10 and 11 we show a lever 12 which is designed so that it both engages 110 the thread 5 and serves as a guide to enable the thread to take proper position with respect to this lever. When this type of lever is used, the guard and guide as shown at 9 can be dispensed with. This lever is mounted in the same position as the lever 12 above described; but in addition to the longer arm and the shorter arm to be engaged by the arm 15, it carries at the end of the longer arm a cross piece 51 terminating in a hook 120 or projection 52. When this lever is mounted on the arm 6, the cross-piece 51 will be in about the same position as the guard 9; and the forward edge of the cross-piece 51 will be curved to about the same extent, and be 125 of approximately the same length as the curved edge 14 of the guard 9. Consequently when one desires to make the thread 5 engage the lever he merely places it on the curved edge of the portion 51 and lets it 130

slip down until it is stopped by the hook 52; this action being the same as when the thread is placed on the edge 14 of the guard 9 and slips down into engagement with the 5 fork at the end of the above described lever 12. As shown in Fig. 11, the hook 52 extends in about the same direction as the longer arm of the lever 12.

Having described our invention, what we 10 believe to be new and desire to secure and protect by Letters Patent of the United States is:—

1. The combination of a casing for the stop-mechanism of a knitting machine, a 15 plurality of arms mounted on the casing, a rock-shaft on each arm projecting to the inside of said casing, arms on the rock-shafts inside the casing projecting alternately in opposite directions, and tension devices for 20 said shafts to hold them yieldably in the required position, said devices comprising a set of springs for engaging the arms on the rock-shafts extending in one direction around the casing and a second set of springs 25 for engaging the arms on the rock-shafts extending in the opposite direction around the casing.

2. A tension device for the stop-mechanism of a knitting machine having rock- 30 shafts to engage the thread-levers thereof, said device comprising a disk, and a plurality of arms mounted on the disk, said arms having eyelets at their outer ends and having their inner ends to be attached to 35 springs connected to said shafts inserted in holes in the rim of the disk.

3. A tension device for the stop-mechanism of a knitting machine having rock- 40 shafts to engage the thread-levers thereof, said device comprising a disk having a bearing 45 projecting from one face, a second disk

having a bearing projecting from one face, said bearings abutting each other to keep the disks spaced apart, and arms carried by each of said disks yieldably connected to said 50 rock-shafts and projecting from the rims of same.

4. A tension device for the stop-mechanism of a knitting machine having rock-shafts to engage the thread-levers thereof, 55 said device comprising a pair of spaced-apart disks having abutting bearings, a pin pivotally secured to one disk and having a threaded opening, an adjusting screw engaging said opening, a pivoted pin having a threaded opening secured to the other disk the first disk having a slot through which the second named pin projects, and a second adjusting screw for engaging the pin on the second disk, and located beside the first 60 adjusting screw, said disks being yieldably connected with said rock-shafts.

5. The combination of a head for the stop-mechanism of a knitting-machine, an arm thereon, and a pivoted thread-engaging element 65 on the arm, said element having a curved cross piece adapted to guide the thread into engaging position with respect to said element.

6. A lever for the stop-mechanism of a 70 knitting machine comprising a pair of arms, one of said arms having a cross piece provided with a curved edge to serve as a thread-guide and terminating in a hook, to hold the thread, and the other arm adapted 75 to be engaged to hold the lever in operative position.

In testimony whereof, we have signed our names to this specification this 26th day of June, 1918.

WILBUR C. POTTER.
EDW. H. STINES.
